DESIGN FOR A TRUNDLE TOY

Jesse Hill, New York, N. Y.

Application April 19, 1946, Serial No. 128,771

Term of patent 3½ years

(Cl. D34—15)

To all whom it may concern:

Be it known that I, Jesse Hill, a citizen of the United States of America, residing at 371 Fort Washington Avenue, New York city, county and State of New York, have invented a new, original, and ornamental Design for a Trundle Toy, of which the following is a specification, reference being had to the accompanying drawing, forming part thereof, and in which:

Figure 1 is a top plan view of a trundle toy, showing my new design.

Figure 2 is a side elevational view of same, while

Figure 3 is a transverse view, substantially in section thereof.

I claim:
The ornamental design for a trundle toy, as shown.

JESSE HILL.
